UNITED STATES PATENT OFFICE

133,430

DESIGN FOR A COMBINED LOCOMOTIVE AND TENDER

Henry Dreyfuss, New York, N. Y., assignor to The
New York Central Railroad Company, New
York, N. Y., a corporation of New York

Application November 14, 1941, Serial No. 104,157

Term of patent 14 years

To all whom it may concern:

Be it known that I, Henry Dreyfuss, a citizen of the United States of America, residing at 171 W. 57th Street, in the county of New York, city of New York, and State of New York, have invented a new, original, and ornamental Design for a Combined Locomotive and Tender, of which the following is a specification, reference being had to the accompanying drawings, forming part thereof.

Figure 1 is a perspective view of a combined locomotive and tender showing my new design.

Figure 2 is a front elevation of the same.

The side opposite that shown in Figure 1 is substantially the same as illustrated and the rear end thereof is conventional.

I claim:

The ornamental design for a combined locomotive and tender, substantially as shown and described.

HENRY DREYFUSS.
